UNITED STATES PATENT OFFICE.

ALBERT MAURICE AUBERT, OF BILLANCOURT, FRANCE.

FIREARM.

1,328,475.

Specification of Letters Patent. Patented Jan. 20, 1920.

Application filed July 3, 1917. Serial No. 178,505.

To all whom it may concern:

- Be it known that I, ALBERT MAURICE AUBERT, citizen of the French Republic, residing at 3 Rue de la Ferme, Billancourt, 5 Seine, France, have invented certain new and useful Improvements in Firearms; and I do hereby declare the following to be a full, clear, and exact description of the invention, such as will enable others skilled in 10 the art to which it appertains to make and use the same, reference being had to the accompanying drawings, and to letters or figures of reference marked thereon, which form a part of this specification.
- 15 This invention relates to portable fire arms possessing stability during firing and which enable either deliberate firing, or more or less rapid firing, to be performed at will. The invention, moreover, relates to an ar- 20 rangement of the principal elements, namely, the stock or butt, the trigger and the barrel, and of other parts, whereby a fire arm is produced which permits of firing, and particularly automatic firing, in a position of 25 static equilibrium of the weapon, owing to the physiological effects and the reflex effects of the individual being rendered null or favorable during firing, and the recoil of the weapon under the effect of the mechanical 30 reaction due to firing being avoided, in such manner as to augment the precision and the rapidity of the sighting whatever may be the rapidity of the automaticity of the firing and the variations in that automaticity.
- 35 The butt is arranged perpendicular to the barrel, and in order to maintain the supporting action of the fore-finger this finger is not used for firing. The trigger is arranged at the side of the fire arm, and the thumb is 40 used to actuate the trigger.
- Referring to the drawings, in which like parts are similarly designated—
- Figure 1 is a side elevation of an automatic pistol constructed according to this 45 invention.
- Fig. 2 is a similar view illustrating the improvements applied to an automatic rifle.
- In these two figures, the weapon is not furnished with a radiator for cooling pur- 50 poses.

Fig. 3 is a side elevation and Fig. 4 is

partly a transverse section and partly an end elevation of a pistol fitted with a radiator.

Fig. 5 is a side elevation of a rifle fitted with a radiator.

In all the figures, the weapon is repre- 55 sented in the position for firing.

1 is the barrel, 2 is the butt the front face of which is perpendicular to the barrel. The butt is hollow and serves as a magazine for 60 the cartridges. Preferably it incloses a suitable arrangement operated by the automatic breech shoe and which, at each operation, brings a new cartridge into the breech chamber after the firing of each shot, 3 is the 65 automatic slide, sliding parallel with the barrel and pierced with an opening for the ejection of the cartridge and also for the eventual hand charging. 4 is the trigger, movable about an axis 5, which regulates the 70 fire and which for this purpose presents a nose 12 capable of engaging in a notch 13 in the automatic slide 3, the trigger is duplicated on the other side at 4^a, a hinge longitudinally formed upon each trigger permits 75 the folding of the trigger toward the top, so that the trigger which is not in use may be folded against the weapon. 6 is a link by which the barrel 1 is connected with the frame 7 of the weapon (Fig. 1). 8 is an 80 arm or projection fixed on the barrel and taking between two springs 9 and 10 respectively, these springs being housed in the part 7. When the weapon is furnished with a radiator, as such radiator occupies 85 the central part, a similar pair of springs is disposed on each side, as seen in Fig. 4 at 9, 10, 9^a and 10^a. A cartridge 11 is indicated in Fig. 1 in the barrel and ready for 90 firing.

The trigger 4 is maintained in position owing to the fact that it has an arc-shaped part carrying a cam 14 which rests against a hook 15^a on a part of the sear 15 pivoted at a. The last-named is operated by a 95 spring, b, which presses the hook 15^a against the cam 14. Under the action of this spring, the part 15 tends to maintain the front part of the trigger 4 against the automatic slide 3; the thumb tends, on the contrary, to press 100 the nose 12 of the trigger against the slide and to cause it to enter the notch 13 when

it is opposite the same, at the same time disengaging the catch or sear formed by the upper part of the part 15 and which engages the projection formed upon the hammer 16, the function of which is to strike the percussion or firing pin 17. Also beneath this hammer there is a presser which is pressed against the hammer by a spring 18. The depression of the thumb to a sufficient extent produces, therefore, the release of the hammer owing to the action of the cam 14 and the shot is fired.

It may now be mentioned how the marksman is able to regulate the speed of the automatic firing by producing a more or less energetic braking action upon the automatic slide by means of the nose 12 of the trigger 4. The frictional action between the two surfaces differs according to the direction of movement of the slide. When the slide recoils, the action of the thumb is not comparable with the action of the recoil which is predominant and tends to remove the brake since it considerably reduces the friction. When the slide returns, on the contrary, its action is again predominant (this time under the action of the spring) but the thumb acts then in the same sense, that is to say it tends to wedge the two surfaces; in these conditions, the modifications of pressure of the thumb effect variations in the braking action to any value from zero up to complete blockage and arrest of the slide. In order to release the latter it is necessary to lighten the pressure of the thumb; now, the latter is the inverse action of that required for pressing the nose 12 of the trigger into the notch 13 in the slide. Therefore a shot will only be fired if the pressure of the thumb be renewed. Thus the variation of the counter pressure of the thumb controls the periodicity of the firing.

The weapon illustrated in the drawing is supposed to be furnished with a double safety device for rendering firing impossible when the weapon is not in actual use. Such safety device may comprise a hand lever 19 and a catch device 20. The hand lever 19, at its inner end, engages, by means of a nose or projection, with the hammer 16 the function of which is to strike the percussion or firing pin. As the lever 19 is made to project from the rear of the butt, it is depressed and disengages from the hammer 16 when the weapon is taken in the hand or is placed against the shoulder. The lever 19 is within the butt, whereas the catch 20 is arranged externally thereof upon a pivot, and the lowering of the front portion of this catch 20 causes it to obstruct the trigger, the rising of the rear part at the same time bringing the rear extremity into engagement with the notch 21 or the notch 22 of the automatic slide, for the purpose 65 of maintaining the latter in one or other of

its extreme positions. The catch is retained in the desired positions by any appropriate detent arrangement. If desired, the catch might be made to act upon the lever 19 in order to enhance the safety.

It is obvious that any other safety device could be substituted for that above described and also that any other percussion arrangement could be used. Importance attaches, however, to the trigger 4 furnished with the nose 12 capable of being pressed against the automatic slide and entering a notch therein, and also furnished with a cam device for actuating the percussion devices.

The means for cooling the barrel, owing to its disposition, co-operates to assure for the weapon, whether a pistol, Figs. 3 and 4, or a rifle, Fig. 5, ballistic qualities, the center of gravity being disposed distantly from the axis of fire and the over-balance which could result from this addition being diminished. This cooling arrangement comprises a sheath 23 of metal which is a good conductor of heat, such as copper for example, and which abstracts the heat from the barrel and conducts it into the radiator 24, also of copper, the fins of which are arranged vertically.

A hinge 26 and pins or bolts 27 permit of rapid fixing and dismounting of the radiator, while affording a secure mode of fastening. The radiator 24 has the most elongated form possible so as to bring the center of gravity as far as possible from the axis of the barrel while also assuring an energetic cooling, as the difference in temperature between the upper and lower parts is very great. The radiator is only secured to the barrel, so as to permit of the free movement of recoil. The heat which comes from the heated barrel is imparted to the upper part of the surrounding air.

I claim:—

1. In an automatic fire arm, the combination with the frame and the breech slide thereon, said slide having two notches; of an arcuate shaped trigger pivoted in the frame, a trigger lever thereon projecting at the side thereof for operation by the thumb, said arcuate trigger having a nose for engaging said notches.

2. In an automatic fire arm, the combination with the frame and the breech slide thereon having notches; of an arcuate trigger member mounted in the frame, said member having a nose for engaging said notches, and two triggers secured to said member one at each side of the frame for operation by the thumb, said triggers having their thumb-engaging parts hinged, whereby they may be folded against the frame when not in use.

3. In an automatic fire arm, the combination with the frame and the breech slide thereon; said slide having notches in its

lower face; of an arcuate trigger member mounted in the frame, said member having a nose for engaging said notch and a sear-actuating cam at the side thereof; a trigger secured to said member at the side of said member and frame for operation by the thumb and having its thumb engaging portion hinged, whereby it may be folded against the side of the frame.

10 4. In an automatic fire arm, the combination with the frame, the barrel secured thereto and the breech slide on said frame and slidable over said barrel, of a radiator

having a barrel portion secured to the barrel beneath said slide, and depending radiator 15 plates secured to said portion, whereby said slide will move back and forth over the radiator.

In testimony that I claim the foregoing as my invention, I have signed my name in 20 presence of two subscribing witnesses.

ALBERT MAURICE AUBERT.
